UNITED STATES PATENT OFFICE.

ALBERT W. MILLER, OF RIVERSIDE, CALIFORNIA, ASSIGNOR OF ONE-HALF TO
ELIZABETH C. BRYAN, OF RIVERSIDE, CALIFORNIA.

COIL-FORMING MACHINE.

1,349,903.

Specification of Letters Patent. Patented Aug. 17, 1920.

Application filed September 18, 1919. Serial No. 324,646.

To all whom it may concern:

Be it known that I, ALBERT W. MILLER, a citizen of the United States, residing at Riverside, in the county of Riverside, State 5 of California, have invented a new and useful Coil-Forming Machine, of which the following is a specification.

This invention relates to coil forming machines for winding helical springs of either 10 open or closed formation, to produce compression or tension springs.

The object of the invention is to provide an improved device for coiling a single length of wire upon a rotatable mandrel to 15 conveniently and accurately form a coil spring or a coil for any desired purpose, and to further provide a means for gaging the convolutions of the coil to produce a spring of the desired pitch, the normal position of 20 said means being invariable and the regulation of the pitch of the spring depending upon the manner in which the wire is threaded into the machine.

Another object is to provide a machine of 25 the character adapted to coöperate with mandrels of various sizes and to provide an operating handle adapted to be detachably clamped to said mandrels.

A further object is to provide means for 30 guiding the wire at a point closely adjacent the mandrel so as to control the terminal end of the wire as the wire supply becomes exhausted.

Other objects and advantages will be apparent from the following description of 35 the accompanying drawings illustrating a preferred form of embodiment of the invention and forming a part of this specification.

In the drawings:

40 Figure 1 is a front elevation of my improved coil forming machine.

Fig. 2 is a top plan view thereof.

Fig. 3 is a central transverse section.

Fig. 4 is a side elevation.

45 Fig. 5 is a central longitudinal section.

Fig. 6 is a detail view of the wire control mechanism showing the parts in position for threading the wire into the machine.

Fig. 7 is a detail section on line x^7-x^7 of 50 Fig. 5.

Fig. 8 is a detail section on line x^8-x^8 of Fig. 4.

The frame or support for the mechanism as illustrated in the drawings comprises a 55 rectangular frame 1 bolted or otherwise se-

cured to a bench or table, or firmly held by any other desired means. The side walls 2-3 of said frame are provided with apertures 4-5 forming clamp edges 6-7 of inverted V-shape. Vertically slidable within the frame 1 is a friction clamp slide 8 which is of inverted U-shape with the side limbs 9-10 thereof lying closely adjacent the side walls 2-3 of the frame and provided with apertures 11-12 forming V-shape clamp edges 13-14 adapted to coöperate with the clamp edges 6-7 of the frame to frictionally grip a mandrel 15, as shown in Fig. 3. The limbs 9-10 of the clamp slide 8 are maintained in spaced relation by a tie rod 16 secured in the lower ends of said limbs and the slide is vertically guided upon the frame by guide plates 17-18 which are secured, respectively, to the lower ends of the slide limbs 9-10 with their opposite ends bent 70 outwardly providing ears 19 engaging the opposed vertical edges of the side walls 2-3 of the frame.

A clamp screw 20 has a screw-threaded engagement through the top plate of the 80 frame 1 and is rotatably retained within a bore in the slide 8, a handle 21 being provided for turning the screw 20.

The mechanism above described provides a frame for the machine, having incorporated therein a means for frictionally gripping mandrels of various diameters. 85

The mandrel 15 extends through the frame and a handle 22 is adapted to be clamped thereto, serving as a means for rotating the 90 mandrel and for other purposes as will hereinafter be explained. The clamp end of the lever is bifurcated to form opposed limbs 23-24 provided with apertures forming V-shaped mandrel engaging edges 25-26, respectively, and pivotally journaled in the ends of said limbs and positioned therebetween is a clamp member 27 having a spirally contoured clamp edge 28 adapted to wedgingly engage the mandrel. A handle 95 nut 29 has a screw threaded engagement with the pivot bolt 30 of the clamp member 27 and serves to compress the limbs 23-24 of the handle into clamping engagement with the clamp member and retain said 100 member in set position. The gage device for controlling the pitch of the spring to be coiled is carried by a rod 32 which is loosely journaled in opposed plates 33-34 secured to and projecting beyond the side walls 2-3, 110

respectively, of the frame. It is obvious that these plates may be eliminated and that suitable ears may be extended outwardly as integral parts of the frame.

- 5 Secured to one end of the rod 32 is a gage supporting lever 35 and spaced from the plate 34 by a loose spacing collar 36 is a series of sector shaped gage plates 37 all loose on the rod 32 and retained against rotary 70 movement relative to the lever 35 by a stud 38 secured to said lever and projecting through alined orifices in the gage plates.

10 The opposite end of the rod 32 has a screw-threaded engagement with a wing-nut 39 which engages the outer surface of the plate 33 for the purpose of translating the rod 32 to provide frictional tension on the wire stock as will later be described.

- 15 A guide lever 40 is pivoted on the gage 20 supporting lever 35 and extends inwardly to normally lie between the said lever 35 and the series of gage plates with a notch 25 formed in the lower edge of the lever 40 engaging over the rod 32. The inner upper edge of the lever 40 is provided with a horizontal shelf 42 extending as a guide bridge over the gage plates and provided with a downturned lip 43 on its free end. A relatively wide guide roller 44 is rotatably 30 journaled on the lever 40 and a stud 45 is fixed thereon in position to engage into a notch 46 formed in the lower edge of the lever 35. When the lever 40 is in normal 35 position in relation to the lever 35 it is frictionally clamped thereto by a handle nut 47 which has a screw threaded engagement with stud 45 and clampingly engages the side of the lever 35. The lower edge of the inner end of the lever 40 from the points 40 48, 49, 50 is tapered from the side adjacent the lever 35 upwardly (see Figs. 5 and 8) forming a lower knife edge, the particular purpose of which will later be pointed out.

- 45 When the lead end of the wire stock is inserted into the machine preparatory to a coil forming operation, said lead end must be secured to the mandrel or to the operating handle and in the present instance I illustrate a means for attaching it to the handle, 50 which means comprises a bolt 51 loosely inserted through alined apertures in the limbs 23-24 of the handle 22, the aperture in the limb 23 being square and the inner end of the bolt having a square shank to prevent 55 said bolt from turning. The outer end of the bolt shank is threaded for coöperation with a wing-nut 52 and the square portion of said bolt shank is provided with a vertical transverse aperture 53 positioned adjacent the bolt head and of a size to accommodate the largest size of wire which the machine is designed to handle. This structure provides a means for clamping the lead end of the wire stock, of various sizes, to the 60 handle.

65 The operation of the machine, including the preliminary adjustments and the threading or entraining of the wire stock into the machine will now be described.

The proper size mandrel is first selected 70 and inserted in the frame between the clamp edges 6-7 of the frame and the clamp edges 13-14 of the slide 8 after which the clamp screw 20 is operated to provide sufficient clamping tension on the mandrel to prevent 75 a free turning of said mandrel while at the same time allowing it to be forcibly turned in a wire coiling operation and translated longitudinally as the convolutions of the spring are formed. The operating handle 80 22 is next placed on the mandrel with the V-shaped edges engaging the mandrel, the clamp member 27 being then turned until its clamp edge 28 wedgingly engages the mandrel and the handle nut 29 tightened to 85 maintain the clamp member 27 in set position.

The guide lever 40 is released and swings to the position shown in Fig. 6 and the wire stock, as indicated by the reference numeral 90 55, threaded under the guide roller 44 and over the rod 32 and stud 38 between two adjacent gage plates 37 and is then given one or more turns around the mandrel and threaded through the aperture 53 of the bolt 95 51 adjacent the outer surface of the limb 23 of the handle after which the wing-nut 52 is tightened to securely clamp the lead end of the wire stock to the handle. (See Figs. 2, 5 and 7).

100 The guide lever 40 is now restored to normal position and clamped to the lever 35 by tightening the handle-nut 47. Both levers, as a unit, are now rotated on the rod 32 until the lower inner edges of the gage 105 plates 37 engage the mandrel 15 with the outer side surface of the outermost gage plate engaging the last completed convolution of the spring, as shown in Figs. 2 and 5. In these figures the wire stock is shown 110 threaded between the second and third gage plate providing for the production of a spring of a pitch equal to the combined thickness of the first two plates. It will, of course, be understood that to form springs 115 of various other pitches the wire will be threaded between others of the plates as is required.

120 To provide the required tension on the wire stock, the wing-nut 39 is tightened to translate the rod 32, thereby drawing the levers 35-40, the gage plates 37 and the spacing collar 36 against the plate 34 and against each other to produce a variable frictional gripping of the wire stock between the gage plates.

125 The operating handle 22 and mandrel 15 being operated to form a spring of slightly less than the desired number of convolutions, the wire stock is cut as closely to the plates 130

37 as possible, the free end of the wire being wound, springing upwardly until it hits the guide bridge or shelf 42, as illustrated in dotted lines in Fig. 4, after which the mandrel is again rotated to complete the spring. The number of turns produced by the secondary rotation easily determined by trial.

To again thread the wire stock between the gage plates 37 the guide lever 40 is released and turned to the position shown in Fig. 6 and the wire threaded into the machine and attached to the operating handle as previously described. If the next spring to be produced is to be of the same kind and tension as the first, the adjustment of the wing-nut 39 remains as previously set and after the wire stock is again threaded in the machine the lever 40 is normalized, the forward lower knife edge portions 48, 49, 50 thereof engaging between the lever 35 and the first gage plate 37 with a wedging action which will restore the same frictional tension on the wire stock as determined by the above described previous setting.

25 I claim:

1. A coil forming machine including a mandrel, means for rotating the mandrel, means for guiding wire stock to the mandrel, a series of gage plates laterally movable to permit the insertion of the wire stock between any two of them, and means exerting a variable clamping tension on the gage plates to produce a frictional gripping tension on the wire stock.

25 2. A coil forming machine including a mandrel, means for rotating the mandrel, means for guiding wire stock to the mandrel, a gage supporting member, a series of gage plates laterally movable to permit the insertion of the wire stock between any two of them, a lever, and means for translating the lever to compress the gage plates and produce a variable frictional gripping of the wire stock.

45 3. A coil forming machine including a longitudinally movable rotary mandrel, means for rotating the mandrel, means for guiding wire stock to the mandrel, a series of gage plates laterally movable to permit the insertion of the wire stock between any two of them, means exerting a variable clamping tension on the gage plates to produce a frictional gripping tension on the wire stock, and an independent means movable to release the gage plates.

4. A coil forming machine including a longitudinally movable rotary mandrel, means for supporting and frictionally gripping the mandrel, a series of gage plates adapted to engage the mandrel and laterally movable to permit the insertion of wire stock between the plates, and means for clamping the plates together to produce a frictional tension on the wire stock.

65 5. A coil forming machine including a

longitudinally movable rotary mandrel, a frame, a translatory rod journaled in the frame, a series of gage plates loose on the rod and laterally movable for the insertion of wire stock between the plates, means for supporting the plates in relative transverse alinement, and means for translating the rod to compress the gage plates and produce a frictional gripping tension on the wire stock.

6. A coil forming machine including a longitudinally movable rotary mandrel, a frame, a translatory rod journaled in the frame, a gage supporting lever fixed on the rod, a series of gage plates loose on the rod intermediate the lever and the frame and laterally movable to permit the insertion of wire stock between the plates, and means for translating the rod to compress the plates between the lever and frame for producing a frictional gripping tension on the wire stock.

7. A coil forming machine including a frame, a longitudinally movable rotary mandrel supported in the frame, a coil spacing device comprising a series of gage plates freely separable to permit the insertion of wire stock between said plates, and means for compressing the plates to produce a frictional gripping tension on the wire stock.

8. A coil forming machine including a mandrel, a frame, means guiding wire stock to the mandrel, a bifurcated handle providing opposed limbs apertured to provide mandrel engaging edges, an eccentric clamp member pivoted on the handle between the limbs thereof and adapted to wedgingly engage the mandrel, and means for clamping said limbs together to frictionally clamp the eccentric clamp member in set position.

9. A coil forming machine including a mandrel, a frame, means guiding wire stock to the mandrel, a bifurcated handle providing opposed limbs apertured to provide mandrel engaging edges and provided with a bolt receiving orifice, an eccentric clamp member pivoted on the handle between the limbs thereof and adapted to wedgingly engage the mandrel, means for clamping the limbs together to frictionally clamp the eccentric clamp member in set position, a bolt engaging into the bolt orifice and provided with a transverse aperture for receiving the wire stock, and means for translating the bolt to clamp the wire stock between the handle and the head of the bolt.

Signed at Los Angeles, California, this 11th day of September, 1919.

ALBERT W. MILLER.
